UNITED STATES PATENT OFFICE.

EDGAR O. LOEBER, OF CLEVELAND, OHIO.

TELEPHONE-GUARD.

1,140,048.

Specification of Letters Patent. Patented May 18, 1915.

Application filed February 5, 1913. Serial No. 746,261.

To all whom it may concern:

Be it known that I, EDGAR O. LOEBER, citizen of the United States, residing at Cleveland, in the county of Cuyahoga and State 5 of Ohio, have invented certain new and useful Improvements in Telephone-Guards, of which the following is a specification.

My invention relates to a telephone guard, and the object of the invention is to provide 10 a guard for a telephone transmitter which covers the mouth of the transmitter and protects the same from the accumulation of dust as well as to prevent the person who uses the telephone from breathing into the transmitter and thereby depositing disease germs, all substantially as shown and described and 15 particularly pointed out in the claim.

In the accompanying drawings, Figure 1 is a perspective view of a telephone transmitter with my new and improved guard in 20 using position thereon, and Fig. 2 is a sectional elevation of the mouth piece or trumpet of the transmitter with the guard in sectional elevation. Fig. 3 is a plan view of a 25 modification of the guard itself.

The transmitter as thus shown is indicated by *a* and the trumpet shaped mouth-piece thereof by *2*, which is of the conventional flaring type generally in use. The 30 said guard *g* consists of a paper disk of a fairly substantial kind of paper, preferably, so that it will not be too easily torn, and which is provided with two segmental cuts or slits *3* and *4* above and below, respectively, though they might be placed at the sides if preferred and serve the same purpose. The said slits are not concentric one 35 with the other but eccentric as plainly seen in Fig. 3, and so that the guard may be 40 drawn first over the top portion of the mouthpiece at the slit *3* and then over the other at the slit *4*. The border both above and below is then thrown back into locking position as seen in Figs. 1 and 2 and the 45 guard is in place. This construction also provides a central disk portion *5* which is practically separate from the border *6* except at the two side portions indicated by *7* where the two circular slits *3* and *4* terminate. The said central disk *5* and the border 50 are thus held in unity and a tie is produced across the mouthpiece which holds the central disk firmly upon the edge thereof

all around and forms a diaphragm against which the sound of the voice is uttered the 55 same as it would be into the transmitter if this guard were not present. From practical experience where this guard is used it is found that, if anything, the transmission is clearer and more effective through it than 60 without it, even without perforations, but if desired the form shown in Fig. 3 may be used and wherein a few perforations are shown. These, however, are relatively small, mere pin holes, and not such as to transmit 65 either breath or dust to the interior.

I use paper preferably, because it is cheap and serves my purpose but any other material that will serve the purpose may be used.

The border *6* is purposely made of such width and shape as to provide a space for advertising and which is so plainly displayed or exposed that it can scarcely escape observation by a user of the telephone. 75 The peculiar shape and arrangement of the slots *3* and *4* also is original and especially advantageous in this that they serve not only to fix the guard firmly upon the telephone where it cannot be blown off by wind or knocked off in the every day use of the telephone, and the circular or crescent shape is material for the reason that only by this shape can it be placed on the mouth piece, It will be noticed that the actual space between said slots is considerably less than 80 the space across the mouth of said piece and that they can be engaged thereon only by affixing one slot and then the other after the first one is drawn well back over the narrower portion of said mouth piece, as in Fig. 2. Then the other is applied and 85 pressed back also and the face of the guard caused to close the mouth piece uniformly and tightly all around and said slotted portions serve to draw it tight to place as well as to effectually hold the guard in such 90 tightening relation.

What I claim is:

A guard for the mouth of a telephone transmitter consisting of a light flexible material, such as paper, and having a middle portion adapted to cover the said mouth and provided with two oppositely disposed segmental slits eccentric to each other and 105 terminating in the sides of the guard, the

space between the middle of said slits being less than the space between the ends of each slit across said middle portion, whereby the said guard can be hooked over the edge of 5 the transmitter through said slits and both lock the same thereon and spread the middle portion over the mouth of the transmitter.

In testimony whereof I affix my signature in presence of two witnesses.

EDGAR O. LOEBER.
